UNITED STATES PATENT OFFICE.

FINLEY W. NOTT, OF BLUEFIELD, WEST VIRGINIA.

WRENCH.

No. 893,093.

Specification of Letters Patent.

Patented July 14, 1908.

Application filed October 25, 1907. Serial No. 399,137.

To all whom it may concern:

Be it known that I, FINLEY W. NOTT, a citizen of the United States, and resident of Bluefield, in the county of Mercer and State 5 of West Virginia, have invented an Improvement in Wrenches, of which the following is a specification.

My invention is an improvement in wrenches, and consists in certain novel constructions and combinations of parts herein- 10 after described and claimed.

Referring to the drawings forming a part hereof, Figure 1 is a side view of the wrench partly in section. Fig. 2 is a rear view of 15 the upper end of the same; and Fig. 3 is a section on the line 3—3 of Fig. 1, looking in the direction of the arrow.

The present embodiment of my invention comprises a chambered handle A, provided 20 at one end with a fixed jaw a³, secured to the handle by means of screws a, the said fixed jaw having an opening therethrough in which the end of the handle is received, the opening being closed at the outside of the 25 fixed jaw by means of a plate a⁰, secured to the fixed jaw by the screws a^x. A slot a' leads from the front side of the handle to the chambered portion thereof, and the said front side is provided with a series of up- 30 wardly facing ratchet teeth a², for a purpose to be presently described.

A movable jaw B is provided with an opening b therethrough through which slides the handle A, the opening b being of some- 35 what greater cross section than the handle in order to slip freely thereon. The co-acting faces of the fixed jaw a³ and the movable jaw B are corrugated, as at a⁴, b¹⁰, whereby to more securely engage the object C.

40 The rear end of the movable jaw is cut away except at its top and bottom, as shown in Figs. 1 and 2, and a plate spring b' is arranged in the said opening to press against the handle A, the ends of the spring resting with- 45 in openings b⁰, and b², in the jaw. The spring is arched toward the handle as shown in Fig. 1, and normally presses the handle to- ward the opposite side of the opening.

The lower edge of the opening through the

movable jaw is provided with a tooth or 50 pawl b^x, for engaging the ratchet teeth a², and a spring b⁶ is arranged within the chambered portion of the handle, the said spring having one end secured to the plate a⁰ by a screw eye b⁶, and the other end by a screw 55 eye b⁷ projecting through the slot a' before described.

The spring b⁶ normally tends to draw the movable jaw toward the fixed jaw, and the 60 bottom edge b^x of the movable jaw acts as a pawl to prevent a reverse movement, thus retaining the jaws in their adjusted position. By pressing on the portion b¹¹ of the movable 65 jaw as shown in Fig. 1, the pawl edge b^x is released from the ratchet teeth, and the movable jaw may be moved away from the fixed jaw.

It will be evident from the description, 70 that the movable jaw is slidable on the handle and has a limited movement transversely thereof. Since the pawl is rigid with respect to the movable jaw, a movement of the jaw will move the pawl into and out of engagement with the teeth.

75

I claim—

A wrench comprising a handle provided with a fixed jaw, and having a chambered portion adjacent to the jaw, the face of the handle adjacent to the operative face of the 80 jaw being longitudinally slotted and provided with ratchet teeth, a movable jaw having an opening for receiving the handle, said opening being of greater cross section than the cross section of the handle, a screw-eye 85 connected with the movable jaw and projecting through the slot, a spring having one of its ends connected with the screw-eye and the other to the handle in the chambered portion, a pawl on the movable jaw for en- 90 gaging the ratchet teeth, and a spring acting normally on the movable jaw to force the pawl into engagement with the ratchet teeth.

FINLEY W. NOTT.
